UNITED STATES PATENT OFFICE.

WALTER BRUCE WILLS, OF BALTIMORE, MARYLAND.

WIRE HANDLE.

Application filed February 10, 1926. Serial No. 87,275.

This invention relates to wire handles for kitchen and other utensils and methods of making the same.

In the manufacture of wire handles for such purposes production in quantity is essential to economy and consequently such handles are formed on what are known as automatic wire forming machines. Standard automatic wire forming machines are not designed to form lengths of wire greater than twenty-four inches. The result is that the manufacture of a handle using a greater length of wire cannot be accomplished on such a machine but several operations are necessary involving the use of two or more machines or of considerable hand work. It is true that a special machine might be devised for such greater lengths but these larger machines are necessarily slow of operation and expensive of construction while having but a limited use on such greater lengths.

One important object of the present invention is, therefore, to provide a novel construction of wire handle of this class which can be made from a plurality of lengths of wire none of which is of greater length than twenty-four inches and each of which may be made on a standard wire forming machine.

A second object of the invention is to provide a simple and economical means for connecting the parts of such a handle and to utilize for such connecting means the sleeve which is commonly employed in handles of the type formed by two wires laid side by side without twisting.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a plan view of a form of handle and utensil supporting ring as constructed in accordance with this invention.

Figure 2 is a side elevation thereof.

Figure 3 is an enlarged perspective view

of a clip used in forming the connecting sleeve for the two parts of the handle.

Figure 4 is an enlarged detail view showing the first step in joining to two parts of the handle by such clip.

Figure 5 is a somewhat similar view showing the completely formed sleeve.

Figure 6 is a greatly enlarged section on the line 6—6 of Figure 5.

In the form of the invention here illustrated there is shown a two part wire handle, one part being preferably called the utensil supporting section and the other part being termed the handle proper or hand grip section.

The utensil supporting section consists of a single length of stout wire which is bent to provide a utensil encircling band 10, this band being shaped to conform to the utensil and having its ends brought together and extended upwardly as at 11. From the upper ends of the parts 11 extend lateral arms 12 which terminate preferably in end faces lying in the same vertical plane. The portions 11 and 12 are arranged side by side and in contact throughout their extent.

The hand grip section also consists of a single length of wire bent intermediate its ends to provide a U-shaped grip 13 the legs of which converge as at 14 and terminate in parallel contacting portions 15 having terminal faces lying in the same vertical plane.

To connect these portions there is provided a substantially U-shaped clip having a base 16 provided with a longitudinally extending inwardly struck rib 17 and also having sides 18.

In assembling the portions 12 and 15 are brought into alignment with their ends abutting and the sides 18 are then bent around the portions 12 and 15 as best seen in Figure 6. Finally a series of staggered punchings are made in the bent side portions as at 19 and it is important that these punchings should be staggered to keep the two sides formed by the wires from spreading apart. Thus a handle requiring more than twenty-four inches of wire can be easily made from two sections each using not more than twenty-four inches of such wire, the two sections being firmly united without soldering, brazing or the like.

Moreover, it will be seen that the clip or sleeve here used is practically the same as that ordinarily used for holding the contacting parts of handles formed from one piece of wire from spreading.

There has thus been provided a simple wire handle for utensils and an improved method of manufacturing the same.

Having thus described the invention, what is claimed as new, is:

1. The method of assembling a two piece wire utensil consisting in forming a supporting section with parallel terminal portions having their end surfaces lying in the same transverse plane, forming a handle section with parallel terminal portions having their end surfaces lying in the same transverse plane, juxtaposing said plane surfaces in abutting relation and alining the terminal portions of the supporting section with the terminal portions of the handle section, wrapping a clip sheet around said abutting terminal portions and indenting

the clip into frictional contact with all of the said terminal portions.

2. A utensil comprising a section of wire formed as a support and having parallel terminal portions provided with plane end surfaces lying in a transverse plane common to both, a second wire section formed as a handle and with parallel terminal portions having their end surfaces lying in a transverse plane common to both, the end surfaces of the terminal portions of the support abutting with the end surfaces of the terminals of the handle and abutting each other, the terminals of the support being alined with the terminals of the handle, a clip sheet disposed around all of said terminal portions and in close contact therewith and bridging all of said abutting surfaces, said clip having indentations which frictionally engage all of said terminal portions.

In testimony whereof I affix my signature.

WALTER BRUCE WILLS.
